Assistant Examiner—Antoine D. Davis
Attorney, Agent, or Firm—Davis, Bujold & Streck

[73] Assignee: CABLOPTIC S.A., Switzerland

[57] **CLAIM**
The ornamental design for automatic optical fiber alignment instrument, as shown.

[**] Term: 14 Years

DESCRIPTION

[21] Appl. No.: 259,112

FIG. 1 is a top plan view of an automatic optical fiber alignment instrument showing our new design;

[22] Filed: Oct. 18, 1988

FIG. 2 is a front elevational view;

[30] Foreign Application Priority Data

FIG. 3 is a left side elevational view;

Apr. 18, 1988 [XH] Hague 010767

FIG. 4 is a right side elevational view;

[52] U.S. Cl. D10/46

FIG. 5 is a top, front and left side perspective view, with the protective hood shown in a open position and drawn on a reduced scale;

[58] Field of Search D10/75, 46; 250/227.21;

350/96.13, 96.14, 96.15, 96.16, 96.18, 96.2, 96.21, 96.22; 370/3

FIG. 6 is a top, front and left side perspective view, with the protective hood shown in a closed position and drawn on a reduced scale;
